UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

INSULATOR.

Application filed July 22, 1922. Serial No. 578,756.

The invention relates to insulators, and more particularly to the type used for attaching wires to buildings or other supports, and its object is to provide an inexpensive form of insulator that may be readily attached to the support and that will accommodate line wires coming to or extending from it at different angles.

The invention further consists in the several features hereinafter set forth and more particularly defined by claims at the conclusion hereof.

In the drawings: Fig. 1 is an elevation view of an insulator embodying the invention; Fig. 2 is a rear end view of the insulator; Fig. 3 is a vertical sectional view through the insulator; Fig. 4 is a view similar to Fig. 3, showing a modified form of construction for anchoring the attaching member of the insulator, and Fig. 5 is a view similar to Fig. 3 showing a modified form of the wire-receiving portion of the insulator.

In each instance the insulator includes a bracket 6, preferably of porcelain and of square or polygonal shape so that it may be engaged by a wrench. In Figs. 1 to 3, inclusive, and Fig. 5, a threaded attaching member 7 has its enlarged polygonal end 8 disposed in an opening 9 in the base portion of the block and securely fastened to the block by a cement filler 10. In Fig. 4 the threaded attaching member 9' has bifurcated portions 8' extending well into the body of the insulator in openings 11 and secured to the insulating block by a cement filler 12. While the member 7 is shown as a lag screw it may be a threaded member of uniform diameter, such as a bolt, and connected to a support by means of a nut, as will be readily understood.

In Figures 1 to 4, inclusive, the line-receiving part of the insulator consists of a member 13 having an eye or hook 13' having its shank 14 disposed within an opening 15 in the block and secured therein by a cement filler 16, the inner end of the member 13 having an enlarged head 17, preferably of polygonal formation to prevent turning.

In Fig. 5 the line-receiving member is formed by a bolt 18 passing through a transverse opening 19 in the insulator block and

carrying a bail 20. In any of the above forms the insulator may be screwed into a wooden support, where the threaded member is a lag screw, and in that way have its base firmly clamped to the support, but where the member 7 is a bolt the insulator may be screwed into the nut of the bolt or into a threaded metal support to secure it in place, the square formation of the block permitting the operator to use a wrench in turning the insulator.

In either instance the line wire may be passed through the eye of the member 13 or through the eye formed by the bail 20 so that the line wire may be taken off at different angles from the insulator. It will be understood that a hooked end may be used in place of the eyed portion of the member 13 and permit of taking off the line wire at different angles.

While I have shown the block form of insulating material, such as porcelain, it will be understood that this block may be formed of other insulating material, such as molded insulating material, so that the metal parts may be secured in position in such material during the process of molding, in which case a cement filler is not necessary.

What I claim as my invention is:

1. An insulator comprising a block of insulating material having polygonal tool-receiving sides and having openings at its ends extending into the interior of the block, a threaded attaching member fixedly secured in one of said openings, and a relatively stiff wire-receiving member having a part secured in the other of said openings.

2. An insulator comprising a block of insulating material having openings extending into the block at its ends, a threaded attaching member fixedly secured in one of said openings, and a relatively stiff looped wire-receiving member having a part secured in the other opening, said looped member being adapted to receive a wire from different angles of approach with respect to said insulator body.

3. An insulator comprising a block of insulating material having a flat base and an opening extending therefrom into the body of the insulator, a threaded attaching member fixedly secured in said opening, and a bail carried by the head end of the block

for receiving a wire from different angles of approach with respect to said insulator block.

4. An insulator comprising a block of insulating material having polygonal wrench-engaging sides and having openings at its ends extending into the interior of the block, a threaded attaching screw having a head

non-rotatably secured within one of said openings, whereby the insulator is mounted 10 on a support by the turning of a wrench engaging the polygonal sides, and a relatively stiff looped wire-receiving member having a part secured in the other opening.

In testimony whereof, I affix my signature.
WILLIAM D. KYLE.
